UNITED STATES PATENT OFFICE.

BLIDA F. CHANDLER, OF CHICAGO, ILLINOIS.

TABLE-MAT.

1,387,239.

Specification of Letters Patent.

Patented Aug. 9, 1921.

Application filed September 24, 1917. Serial No. 192,867.

To all whom it may concern:

Be it known that I, BLIDA F. CHANDLER, a citizen of the United States, residing at Chicago, in the county of Cook and State 5 of Illinois, have invented a certain new and useful Improvement in Table-Mats, of which the following is a full, clear, concise, and exact description, reference being had to the accompanying drawings, forming a 10 part of this specification.

My invention relates to table appurtenances and is concerned with table mats or napkins, commonly known as doilies. It is the object of my invention to provide a doily 15 of material which is waterproof, so that its surface can be washed, such as waxed, oiled or enameled cloth, and to provide such a doily which will, of itself, lie flat upon the table and will be of generally attractive 20 appearance.

It is well known that the kind of materials, which I desire to employ and which I have mentioned tend to curl inwardly, that is, toward the waxed, oiled or enameled 25 face which, in use, is the uppermost surface, and therefore they do not lie flat, particularly in small pieces, as when a table is set with doilies rather than a whole cover.

The use of such materials for doilies therefore has not been in vogue and where such 30 materials are used the cover is a whole cover and in most cases fastened to the table top at the edges. In the case of small pieces such fastening means would be out of the question 35 for practical and artistic reasons.

In accordance with the teachings of my invention I employ specific means to make the doily lie flat, notwithstanding its inherent tendency and I employ such means 40 as not only do not mar, but actually enhance, the appearance of the article. I provide means to make the doily lie flat which may be worked into and made a part of the design of the article, (it being usual to provide doilies with artistic designs) and thus 45 avoid evidence of the means to the end.

In the accompanying drawings—

Figure 1 is a plan view of the doily of my invention;

50 Fig. 2 is an enlarged plan view of an edge portion thereof;

Fig. 3 is an enlarged end view of an edge portion thereof; and

Fig. 4 is a cross sectional view taken on the line 4—4 of Fig. 2.

55

The mat or doily itself is shown at *a*, being of waxed, oil or enameled cloth, the waxed, oiled or enameled surface being on top. The design, of any chosen order, is painted upon the waxed, oiled or enameled 60 surface, as indicated at *b*, *b*, it being seen that heavy portions of paint, serving to stiffen the mat, are appropriately disposed along the outer edges and corners of the doily, as illustrated at *c*, *c*. Around the 65 edges the margin *d* is also provided with paint, acting as a border and for the purpose of stiffening the edges of the mat. In addition the edge stitching *e*, *e*, of appropriate color is provided about the entire periphery, 70 the stitching going to the depth of the margin and being carried outside the periphery of the doily, in the nature of looped over-casting. The stitching is of any desirable material, conveniently cotton or 75 woolen yarn.

The result is an attractive appearing mat which is caused to retain its flat condition, due to the heavy painted areas and borders and to the peculiar border stitching which I 80 use, notwithstanding the inherent tendency of the mat or doily, *per se*, to curl.

I claim:

A table mat comprising a surfaced fabric body, a relatively narrow border of the same 85 material as the body, a relatively thick adhesive coating applied to said border giving it additional weight, firmness and rigidity, the connecting part between said body and said border being weakened by a line of 90 closely spaced interstices and stitching passing through said interstices wrapped about and binding said border, said stitching further increasing the weight of said border, whereby the relatively heavy border, 95 through its weakened connection to the body portion prevents curling thereof.

In witness whereof, I hereunto subscribe my name this 18th day of September, A. D. 1916.

BLIDA F. CHANDLER.
